(57) **CLAIM**

The ornamental design for a portable container for saw blades and other table saw accessories, as shown and described.

DESCRIPTION

FIG. 1 is a perspective view of a portable container for saw blades and other table saw accessories showing my new design in the closed position;

FIG. 2 is a perspective view of the container in the open position;

FIG. 3 is a top end view of the container in the closed position;

FIG. 4 is a bottom end view of the container in the closed position;

FIG. 5 is a first side view of the container in the closed position;

FIG. 6 is an opposing side view of the container in the closed position;

FIG. 7 is top view of the container; and,

FIG. 8 is a bottom view of the container.

The broken line showing of the word BOSCH is for illustrative purposes only and forms no part of the claimed design.
